UNITED STATES PATENT OFFICE.

THOMAS BURNETT, OF EUREKA, CALIFORNIA.

BREECH-LOADING FIRE-ARM.

SPECIFICATION forming part of Letters Patent No. 250,495, dated December 6, 1881.

Application filed June 21, 1881. (Model.)

To all whom it may concern:

Be it known that I, THOMAS BURNETT, of Eureka, in the county of Humboldt and State of California, have invented a new and useful 5 Improvement in Breech-Loading Fire-Arms, of which the following is a specification.

My invention relates to that class of breech-loading fire-arms in which the breech-block swings backward and downward.

10 In the accompanying drawings, Figure 1 is a longitudinal vertical section of a gun embodying my improvements. Figs. 2, 3, 4, and 5 are detail views.

Similar letters of reference indicate corresponding parts.

15 A represents the frame, B the barrel, C the swinging breech-block, and D the lever, all of which may be of the usual or any suitable description, the lever and breech-block being 20 connected by a link, e.

The chamber of the breech is reamed or bored out, and in it is inserted my improved cartridge-seat F, which is made in two semi-cylindrical halves, by which construction provision 25 is made for the expansion of the seat in case of the expansion of the cartridge when exploded, so that the exploded shell may be easily withdrawn.

20 The shell-extractor consists of a ring, G, provided with two radial arms, g² g³. It fits in a crotch in the breech-block C, and works on the same pivot, e, with said breech-block. The arm g² works in a notch, b, in the rear end of the chamber and cartridge-seat, and the arm 35 g³ is arranged for engagement with the lever D. When the lever D is operated to open the breech by swinging the breech-block C backward and downward, the nose d of the lever strikes the arm g³ of the extractor and moves 40 it forward, causing the arm g² to move rearward and extract the shell.

H represents a block working on a pivot, h, and provided with a spring, i, which has a tendency to keep its upper portion pushed forward. When the breech is closed the top of 45 this block rests under the rear corner of the breech-block C and securely locks it. The front side of the block H is provided with a cam-surface, and the portion of the lever D which 50 is within the frame and in rear of the pivot a is provided with a corresponding cam-surface.

When the lever is moved downward to open the breech the cam-surface of the lever engages with that on the block H, and forces it backward and out from under the breech-block, 55 so as to allow said breech-block to swing clear in the space provided for it in the frame. When the lever is moved upward to close the breech the spring i presses the block H forward and under the breech-block again. 60

The firing-pin J works in the breech-block C in the usual manner. In the top of the frame A, between the firing-pin and the hammer N, is a groove in which works a sliding bolt, L, which is prevented from working upward by the means of a stud, m, projecting from the groove of the frame and engaging with a groove in the side of the bolt, and also by a hook, l, on the rear end and under side of the bolt engaging with a recess in the frame 70 under the rear end of the groove in which the bolt works.

The top of the rear end of the bolt is provided with a roughened surface or thumb-piece, l², to facilitate its withdrawal. 75

Under the bolt is a spring, l³, to prevent it from working too loosely in the groove or from accidentally dropping out rearwardly. When the bolt is in place in the groove it serves to communicate the blow from the hammer to the 80 firing-pin. When it is desired to move the bolt the hammer is placed at half-cock, and then, by placing the thumb on the thumb-piece l², the bolt may be drawn back and removed from the groove. By this means the accidental discharge of the gun is rendered impossible, as the blow from the hammer, if accidentally lowered, would not be communicated to the firing-pin. 85

To the hammer N is connected the upper 90 branch of the mainspring P, the double portion of which is secured to the frame A in any suitable manner. The lower branch of the mainspring is engaged with the rear end of a lever, Q, the front end of which engages with 95 the trigger R after the manner of a sear.

To the lever Q, between its fulcrum and the trigger, is attached an elastic tongue, q, extending upward and rearward in a curved line, and terminating in a point, so as to form a cam. 100 On one side of the hammer N, in rear of the pivot n, is a stud or projection, s, for engage-

ment with said tongue or cam q , as hereinafter described.

The sear T is pivoted under the hammer, and is provided with two lateral arms, v v^2 , between which the tongue or cam q works. A spring, w , bears against the under side of the rear arm, v , which is provided with a knife-edge for engagement with the cock-notch and half-cock notch of the hammer N . When the hammer is pulled back to cock the gun the stud or projection s strikes the edge of the elastic tongue or cam q , and forces the lever Q down so that its front end will be engaged and held down by the trigger R . This places the lever Q clear of the sear, and allows the spring w to force the arm v upward to engage with the half-cock notch. The parts are then in the position shown in Fig. 1. As the hammer is pulled farther back the elastic tongue springs over the stud or projection s , and the arm v slips into the cock-notch and holds the gun at full-cock. When the trigger is pulled, the lever Q , impelled by the lower branch of the mainspring P , strikes the forward arm, v^2 , of the sear, and disengages the rear arm, v , from the cock-notch, allowing the hammer to descend. The end of the upper arm of the lever D then fits in a notch in the breech block C , in front of the upper end of the block H , and thus assists in locking the breech block.

I am aware that it is not new to construct cartridge-chambers longitudinally divided and with a movable lid to admit the cartridge sideways; but

What I claim as new is—

1. In a breech-loading fire-arm, the combi-

nation, with a cylindrical breech-chamber, of a cartridge-seat, F , made in two semi-cylindrical parts and inserted in said chamber, as shown and described.

2. In a breech-loading fire-arm, the sear T , pivoted under the hammer, and provided with lateral arms v v^2 , the arm v being knife-edged and pressed upwardly by a spring, w , in combination with the trigger, the lever having cam q working between said arms, the mainspring P , and the notched hammer N , as and for the purpose specified.

3. The combination, with the hammer and firing-pin, of the bolt L , having a side groove and sliding in a groove of frame A , of the stud M , projecting from said frame-groove, the rear hook, l , engaging with a recess under the rear end of said frame-groove, the thumb-piece p , and the subjacent spring b^3 , as and for the purpose set forth.

4. The combination, with the swinging breech-block C , of the lever D , having the nose d , and the ring G , having the radial arms g^2g^3 , said ring being arranged on the same pivot as the breech-block and in a crotch thereof, as shown and described.

5. The lever Q , provided with the elastic tongue or cam q , in combination with the trigger R , the mainspring P , and the hammer N , provided with the stud or projection s , substantially as and for the purpose herein described.

THOMAS BURNETT.
